United States Patent Office

Des. 181,893
Patented Jan. 14, 1958

181,893

TABLE FRAME OR THE LIKE

William James Borgen, Waukegan, Ill.

Application February 26, 1957, Serial No. 44,997

Term of patent 14 years

(Cl. D33—14)

Fig. 1

Fig. 2

The dotted line indication of a table top shown in Figures 1 and 2 are for illustrative purposes only.

I claim:

The ornamental design for a table frame or the like, as shown and described.
